UNITED STATES PATENT OFFICE.

ALFRED E. BRADEN, OF TACOMA, WASHINGTON.

DESIGN FOR A TIRE.

53,100.

Specification for Design.

Patented Mar. 18, 1919.

Application filed September 23, 1918. Serial No. 255,370. Term of patent 7 years.

To all whom it may concern:

Be it known that I, ALFRED E. BRADEN, a citizen of the United States, and a resident of Tacoma, in the county of Pierce, and the State of Washington, have invented a new, original, and ornamental Design for Tires, of which the following is a specification, reference being had to the accompanying drawings, forming a part thereof.

In the drawings Figure 1 is a plan view of my design. Fig. 2 is a perspective cross sectional view of the tire taken along line $x-x$ of Fig. 1.

Copies of this patent may be obtained for five cents each, by addressing the "Commissioner of Patents, Washington, D. C."

My design consists of a circumferential center bead on either side of which are alternate half diamonds and half crosses, both in relief. When viewed together the design forms an alternate succession of diamonds and crosses split by a central bead.

I claim:

The ornamental design for a tire, as shown and described.

ALFRED E. BRADEN.
